CLOTH LAYING MACHINE

Aaron H. Lessen, George H. Rowles, and Cyril F. Dougherty, Baltimore, Md., assignors to The Shirercraft Company, Inc., Baltimore, Md., a corporation of New York

Application August 10, 1936, Serial No. 95,292

15 Claims. (Cl. 270—31)

The present invention relates to cloth laying machines and refers particularly to that type of machine which is adapted to travel back and forth along a table during the cloth laying operation. 5 These machines usually comprise a wheeled carriage and a cloth supporting platform pivotally mounted thereon to permit reversal of the platform when the carriage has reached the end of its travel. While these machines are quite satisfactory in operation, we have found that there is a tendency for the cloth supporting platform to rotate relative to the carriage during the travel of the machine and thus impair the efficiency of the device. It is therefore an object of the present invention to eliminate this undesirable feature and to provide a machine having means for preventing relative rotation of the platform and carriage during its travel. We accomplish this by utilizing one of the cloth guides and mounting the same so that it not only performs its function as a guide but also locks the carriage and platform against relative rotation during the travel of the machine.

A further object contemplates adjustably mounting one or more of the guide rollers, which engage the side edges of the table, on the carriage to adapt the machine for use with tables of various widths or to irregularities in the side edges of the tables.

With the foregoing and other objects in view, the invention will now be more particularly described, reference being had to the accompanying drawings, wherein:

Figure 1 is an elevation illustrating one side of the machine.

Figure 2 is an elevation illustrating the opposite side of the machine shown in Figure 1.

Figure 3 is a top plan view of the machine.

Figure 4 is a vertical section taken on line 4—4 of Figure 3 and

Figure 5 is a detailed view of the adjustably mounted guide rollers.

Generally our cloth laying machine comprises a carriage adapted to travel back and forth along a cloth receiving table and a cloth supporting platform pivotally mounted upon the carriage and provided with one or more cloth guides located adjacent one end thereof. One of these guides is pivotally and swingably mounted upon the platform and has side arms which connect with the cloth guiding portion and which, when in the operative position of the guide, extend downwardly at the sides of the carriage and table and lock these two members against relative rotation.

This machine is also provided with sets of

guide rollers projecting downwardly from opposite sides of the carriage and adapted to engage opposite sides of the table. One set of these rollers are rigidly connected to the carriage but the rollers on the opposite side of the carriage are adjustably mounted thereon and normally spring-pressed inwardly to permit the machine to adapt itself to different widths of tables and also to irregularities in the side edges of the table.

Referring now to the drawings there is disclosed the specific embodiment of our invention wherein the numeral 10 designates the cloth laying machine comprising a carriage 11 and a cloth supporting platform 12 pivotally mounted thereon to permit the platform to be reversed 10 when it reaches the end of its travel on the table. The carriage has a substantially flat horizontal supporting surface 13, preferably of wood, which is supported between spaced metal brackets 14 in any suitable manner, such as by bolts or screws 15. Each bracket is formed at opposite ends with depending arms 16 having inwardly projecting bearings for the reception of wheels 17. The arms of one bracket are also formed with outwardly and downwardly projecting mountings 18 for the 20 reception of guide rollers 19, which are adapted to contact with one longitudinal edge of the cloth receiving table 20 during movement of the carriage.

It will be observed that the other bracket, in addition to having the arms 16, is also provided with a central projection 21 upon which is mounted the means for adjustably supporting the other set of guide rollers. As illustrated in Figures 1 and 5, the lower end of the projection 21 is bent 30 inwardly to form a horizontal mounting or shelf 22. Projecting downwardly from this shelf are a pair of spaced bearings 23 for the reception of the inner ends of levers 24. To the outer end of each lever is secured a roller 25 and both the 35 roller and lever are normally urged inwardly by means of a coil spring 26 having its opposite ends connected to the lever and shelf respectively. In order that the springs may not force the levers and rollers inwardly beyond a certain point, 40 stop pins 27 are provided and these are carried by and project below the shelf.

With the arrangement as above described, the machine is mounted upon the table 20 with the wheels 17 engaging the top surface of the table 50 and adjacent the edges thereof. The rollers 19 and 25, as shown in Figure 4, will engage opposite side edges of the table and thereby guide the machine on the table during the cloth laying operation. By reason of the rollers 25 and the 55

levers 24 being pivotally and adjustably mounted on the projection 20, it will be apparent that the machine may be adapted to tables of various widths or to irregularities in the lateral surfaces 5 or edges of the table.

Any desired means may be utilized for rotatably mounting the platform 12 upon the carriage 11 and in the present instance we provide a boss 28 having an aperture for the reception 10 of a stud or king pin 29. This stud is provided with a head 30 secured in a recess in the platform 12 and a shouldered shank 31 which projects through the boss 28 and is secured against axial movement by means of a nut 32. A washer 33 is 15 positioned upon the boss 28 and interposed between the members 12 and 13 to provide sufficient clearance and eliminate binding between the platform and the carriage. In order that the platform 12 may rotate freely with respect to the carriage, the former has formed therein a plurality 20 of sockets 34 arranged in a circle and lined with suitable metal inserts 35 for the reception of balls 36. The platform 12 is provided in its undersurface with a track 37 adapted to align and contact 25 with the balls 36.

The cloth, shown in dotted lines, may be either in the form of a bolt as shown in Figure 1 or a roll as disclosed in Figure 2. In one instance, it is merely laid upon the platform 12 but if it is 30 in the form of a roll, it will have a rod or shaft extending through the center thereof and this will be rotatably supported between the uprights 38. In either instance, however, the cloth will be fed over stationary guides 39 and 40 respectively and 35 will then be guided onto the table by the guide 41. This element constitutes one of the novel features of this invention and, as clearly shown in Figures 1, 2, and 3, is of substantially U-shaped formation 40 having a horizontal cloth guiding portion 42 and side legs 43 projecting outwardly beyond the planes of the edges of the platform and carriage. The free ends of the legs 43 are bent inwardly as 45 at 44 and are journaled in suitable bearings 45 to permit the guide to swing from an inoperative position above the platform to the operative position shown in Figures 1 and 2. It will be observed 50 that when the guide 41 is in its lower operative guiding position shown in these figures, the arms or legs 43 extend downwardly exteriorly of the side edges of the platform and carriage and thereby lock these two members against relative rotation. As the machine travels over the table and 55 assuming that the guide 41 is in its operative lowered position, the platform 12 is thus retained in a fixed position and prevented from swinging to either side of the table. When the machine reaches one end of the table, and it is desired 60 to reverse the platform, it is merely necessary for the operator to lift the guide 41 to a position above the carriage and platform and then rotate the latter about its pivot. By reason of the ball bearing track, this will be easily accomplished. By lowering the guide 41, the platform 12 will 65 again be locked against rotation and the machine will be ready for its return movement to the other end of the table for laying another layer of cloth.

With the use of our novel machine, it will be obvious that we have provided a structure which eliminates one of the objectionable features of 70 the prior art in that rotation of the cloth supporting platform relative to the carriage is positively prevented during movement of the machine. Furthermore, by adjustably mounting one pair of the guide rollers on the carriage, any 75 inaccuracies in the edges of the table are taken

care of and the machine is adapted for use with different widths of tables.

We claim:

1. In a cloth laying machine, a carriage adapted to travel along a table, a cloth supporting platform movably mounted on said carriage, and a cloth guide carried by one of said members and operable to prevent relative movement between 5 said carriage and platform.

2. In a cloth laying machine, a carriage adapted to travel along a table, a cloth supporting platform movably mounted on said carriage, and a cloth guide carried by one of said members and operable when in operative position to prevent 10 relative movement between said carriage and 15 platform.

3. In a cloth laying machine, a carriage adapted to travel along a table, a cloth supporting platform pivotally mounted on said carriage, and a cloth guide carried by one of said 20 members and operable when in operative position to prevent relative rotation between said carriage and platform.

4. In a cloth laying machine, a carriage adapted to travel along a table, a cloth supporting platform movably mounted on said carriage, and a cloth guide carried by said platform and operable when in operative position to prevent 25 relative movement between said carriage and 30 platform.

5. In a cloth laying machine, a carriage adapted to travel along a table, a cloth supporting platform pivotally mounted on said carriage, and a cloth guide carried by said platform 35 and operable when in operative position to prevent relative rotation between said carriage and platform.

6. In a cloth laying machine, a carriage adapted to travel along a table, a cloth supporting platform pivotally mounted on said carriage, and a cloth guide mounted on said platform to swing from an inoperative raised 40 position to an operative lower position and operable when in its lower position to prevent relative rotation between said carriage and platform.

7. In a cloth laying machine, a carriage adapted to travel along a table, a cloth supporting platform pivotally mounted on said carriage, and a cloth guide journalled on and adjacent one end of said platform to swing from an 50 inoperative raised position to an operative lower position and operable when in its lower position to prevent relative rotation between said carriage and platform.

8. In a cloth laying machine, a carriage adapted to travel along a table, a cloth supporting platform pivotally mounted on said carriage, and a cloth guide comprising a cloth engaging portion and arms connecting said portion and mounted on said platform to swing from a raised 60 inoperative position to a lower cloth guiding position and constituting in said lower position a lock to prevent relative rotation between said carriage and platform.

9. In a cloth laying machine, a carriage adapted to travel along a table, a cloth supporting platform pivotally mounted on said carriage, and a cloth guide of substantially U-formation having a cloth guiding portion and arms 70 connecting said portion and swingably mounted on said platform, said arms when in a lowered position engaging the side edges of said carriage and platform and constituting a lock to prevent relative rotation of said members. 75

10. In a cloth laying machine, a carriage adapted to travel along a table, a cloth supporting platform pivotally mounted on said carriage, and a cloth guide of substantially U-formation having a cloth guiding portion and arms connecting said portion, the end of each arm being pivotally mounted adjacent one end of said platform at one side thereof with the major portion of the arm position in a plane beyond the edges 5 of the platform and carriage whereby the cloth guide may be swung to a lowered operative position and lock said carriage and platform against relative rotative movement.
11. In a cloth laying machine, a cloth supporting carriage adapted to travel along a table, rollers projecting downwardly from said carriage and adapted to engage the side edges of the table to guide the carriage during its travel along the table, and means positioned at one side of the 10 carriage and adjustably supporting one of the rollers to permit movement of the roller relative to the carriage.
12. In a cloth laying machine, a cloth supporting carriage adapted to travel along a table, rollers projecting downwardly from said carriage and adapted to engage the side edges of the table to guide the carriage during its travel along the table, the roller at one side of the carriage being laterally movable with respect 15 thereto and spring-pressed inwardly to allow for different widths of tables.
13. In a cloth laying machine, a cloth supporting carriage adapted to travel along a table, 20
14. In a cloth laying machine, a cloth supporting carriage adapted to travel along a table, a roller projecting downwardly from said carriage at one side thereof and rigidly secured thereto, and roller mounting means at the opposite side of said carriage comprising a lever pivotally mounted on said carriage and urged 25 inwardly, towards said carriage and table, and a roller carried by the outer end of said lever.
15. In a cloth laying machine, a cloth supporting carriage adapted to travel along a table, a roller projecting downwardly from said carriage at one side thereof and rigidly secured thereto, and roller mounting means at the opposite side of said carriage comprising a lever pivotally mounted on said carriage, a roller carried by the outer end of said lever, and spring means 30 connecting said lever and carriage and urging said roller inwardly toward said carriage.
16. In a cloth laying machine, a cloth supporting carriage adapted to travel along a table, a roller projecting downwardly from said carriage at one side thereof and rigidly secured thereto, and roller mounting means at the opposite side of said carriage comprising a lever having one end thereof pivotally mounted on said carriage, a roller carried by the other end of 35 said lever, a coil spring connecting said lever and carriage and urging said roller inwardly toward said carriage, and a stop mounted on said carriage for limiting the inward movement of said lever and roller.
